US0D1018490S

(12) **United States Design Patent** (10) **Patent No.:** **US D1,018,490 S**
(45) **Date of Patent:** **** Mar. 19, 2024**

(54) **IN-VEHICLE AMPLIFIER**

(71) Applicant: **ALPS ALPINE CO., LTD.**, Tokyo (JP)

(72) Inventors: **Hideki Endo**, Ota-ku (JP); **Hiroshi Fujimoto**, Ota-ku (JP); **Masatada Muramoto**, Ota-ku (JP)

(73) Assignee: **ALPS ALPINE CO., LTD.**, Tokyo (JP)

(**) Term: **15 Years**

(21) Appl. No.: **29/871,381**

(22) Filed: **Feb. 17, 2023**

Related U.S. Application Data

(63) Continuation of application No. 29/795,783, filed on Jun. 21, 2021, now Pat. No. Des. 978,822.

(30) **Foreign Application Priority Data**

(57) **CLAIM**

The ornamental design for an in-vehicle amplifier, as shown and described.

DESCRIPTION

FIG. 1 is a perspective view from the front and bottom of an in-vehicle amplifier, showing our new design;

FIG. 2 is a perspective view from the front and top thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines are included for the purpose of illustrating portions of the in-vehicle amplifier that form no part of the claimed design.

1 Claim, 6 Drawing Sheets
